[57] CLAIM

The ornamental design for the cup or similar article, as
shown and described.

DESCRIPTION

FIG. 1 is a side elevational view of a cup or similar
article showing my new design, the side opposite is a
mirror image;

FIG. 2 is an end elevational view taken from the left
side of FIG. 1;

FIG. 3 is an end elevational view taken from the right
side of FIG. 1;

FIG. 4 is a top plan view thereof;

FIG. 5 is a bottom plan view thereof; and

FIG. 6 is a cross-sectional view thereof taken along line
6—6 in FIG. 1.

The characteristic feature of my design resides in the
palmette-like decoration incised into the side wall as
best shown in FIGS. 1 and 2 on the drawing.
